DESIGN FOR A WINDOW CURTAIN

Ralph C. Nicholson, Manhasset Village, Mo.

Application July 20, 1940, Serial No. 93,809

Term of patent 3½ years

To all whom it may concern:

Be it known that I, Ralph C. Nicholson, a citizen of the United States, residing at Manhasset Village, county of St. Louis, State of Missouri, have invented a new, original, and ornamental Design for a Window Curtain, of which the following is a specification, reference being made to the accompanying drawing forming a part thereof, in which the figure is an elevational view of a pair of window curtains embodying my new design.

I claim:

The ornamental design for a window curtain, substantially as shown.

RALPH C. NICHOLSON.
